UNITED STATES PATENT OFFICE.

JACOB J. JANEWAY, OF NEW BRUNSWICK, NEW JERSEY.

WALL-PAPER.

No. 839,787.

Specification of Letters Patent.

Patented Dec. 25, 1906.

Application filed February 3, 1906. Serial No. 299,317.

To all whom it may concern:

Be it known that I, JACOB J. JANEWAY, a citizen of the United States, and a resident of New Brunswick, in the county of Middlesex and State of New Jersey, have invented a new and Improved Wall-Paper, of which the following is a full, clear, and exact description.

This invention relates particularly to improvements in borders for wall and ceiling decoration of the class in which festoons and other open-work effects are produced to disclose the body-paper at various points, the object being to provide a border or ceiling of this character in a continuous roll with blank fillings for the places eventually to be left open, thus giving sufficient strength or reinforce to the paper and permitting of free handling and rolling of the paper without danger of tearing the junction-lines between the blanks and the pattern being perforated, so that said blanks may be readily removed before the border is placed in position.

I will describe a wall-paper embodying my invention and then point out the novel features in the appended claims.

Reference is to be had to the accompanying drawing, forming a part of this specification, in which the figure shows a strip of wall-paper embodying my invention.

Referring to the drawing, 1 designates a decorated border, and 2 the body-paper. As here shown, the border has decorated festoons 3, and it also has decorated effects 4 in

its upper band 5. It is to be understood, however, that the invention is not limited to any particular design excepting such design as is eventually to have openings to disclose the wall or body paper. These openings are shown at 6, and in the openings during the manufacture blanks 7 are arranged. The junctions between the blanks and the pattern are formed by perforated lines 8, and obviously these blanks will materially strengthen the border before the same is desired for use. When the border is to be placed upon a wall, the blanks are to be torn out. The perforations of course permit of easy removal.

Having thus described my invention, I claim as new and desire to secure by Letters Patent—

1. As a new article of manufacture, a wall-paper having an ornamental design and removable portions arranged at various points within the design, the paper being perforated at the outlines of the removable portions.

2. As a new article of manufacture, a wall-paper having a plurality of perforations within its pattern, the said perforations forming the outlines of blanks to be removed.

In testimony whereof I have signed my name to this specification in the presence of two subscribing witnesses.

JACOB J. JANEWAY.
